DESIGN FOR A DRESS

Adelé Brody, Brooklyn, N. Y.

Application April 22, 1939, Serial No. 84,493

Term of patent 3½ years

To all whom it may concern:

Be it known that I, Adelé Brody, a citizen of the United States, residing at Brooklyn, in the county of Kings and State of New York, have invented a new, original, and ornamental Design for a Dress, of which the following is a specification, reference being had to the accompanying drawing, forming part thereof.

Fig. 1 is a front view of a dress showing my design, and

Fig. 2 is a rear view of the dress shown in Fig. 1.

The characteristic feature of my design resides in the combination on the dress disclosed of the embroidered sleeves, including criss-crossing lines of embroidery, as shown, in association with the embroidered lapels, whereon the embroidery follows generally the angular contour of the lapels, as shown.

I claim:

The ornamental design for a dress, substantially as shown and described.

ADELÉ BRODY.
